UNITED STATES PATENT OFFICE.

RICHARD E. ACTON, OF ALEXANDRIA, VIRGINIA.

DESIGN FOR A SPOON.

SPECIFICATION forming part of Design No. 21,835, dated September 6, 1892.

Application filed August 6, 1892. Serial No. 442,391. Term of patent 7 years.

To all whom it may concern:

Be it known that I, RICHARD E. ACTON, a citizen of the United States, residing at Alexandria, in the county of Alexandria and State 5 of Virginia, have invented and produced a new and original Design for Spoons, of which the following is a specification, reference being had to the accompanying drawing, forming part thereof.

10 In the drawing the figure is a face view of a spoon, showing my design.

The leading feature of my design consists in the configuration of the shank of the handle and the figure mounted thereon.

15 The handle-shank A has its side edges curved inward toward its middle, presenting a widened appearance at both ends, the upper end presenting at α the appearance of a pedestal-top. Near the lower edge of the

20 shank its edge curves outward to points α' , whence inwardly-curved lines α^2 extend to and

merge in the outlines of the bowl. Within this bowl is produced at B the representation of a church among trees.

The figure C, represented as standing upon 25 the pedestal-top α , is that of a man in court dress, his right hand grasping his staff and his left resting upon his sword, the face being turned slightly to the left. The figure C is intended to present a miniature likeness of 30 General George Washington, and the representation B a likeness of old Christ Church at Alexandria, Virginia, at which church Washington was an attendant.

What I claim is—

35 The design for a spoon herein shown and described.

RICHARD E. ACTON.
